Attorney

UNITED STATES PATENT OFFICE.

PURVIS E. DEAN, OF BOYNE CITY, MICHIGAN.

HOUSE-WALL STRUCTURE.

Application filed October 15, 1924. Serial No. 743,709.

To all whom it may concern:

Be it known that I, PURVIS E. DEAN, a citizen of the United States, residing at Boyne City, in the county of Charlevoix 5 and State of Michigan, have invented certain new and useful Improvements in House-Wall Structures, of which the following is a specification.

This invention relates to an improved wall 10 structure which I have devised for constructing houses and the like.

I propose to provide a wall structure which is not susceptible to the passage of heat and cold, this end being accomplished 15 by providing dead air spaces between the outer wall facing and the central partition wall, and also between the inner wall facing and said partition wall.

It is a feature of the invention to construct 20 the so-called partition wall in the form of a frame work composed of vertical studs connected together by horizontal pieces and engaging the horizontal pieces and studs in a concrete wall having the surfaces spaced 25 from the outer surfaces of the studding to provide air spaces when the inner and outer wall surfaces are placed in position.

In the accompanying drawings, forming 30 a part of this specification, and in which like numerals are employed to designate like parts throughout the same:

Figure 1 is an outer elevational view of a portion of a house embodying my improved wall structure.

Figure 2 is a horizontal section through 35 the improved wall structure, the section being taken substantially on the plane of the line 2—2 of Figure 3.

Figure 3 is a vertical section through the 40 structure.

Referring to the drawings in detail, it will be observed that the so-called central partition wall comprises a plurality of vertically disposed studs 1, spaced apart in the 45 usual manner. Connected to these studs and arranged at the bottom, center and top, are horizontal connecting pieces 2. The studs are preferably arranged in staggered relation on opposite sides of the connecting 50 pieces, as seen more clearly in Figure 2. Horizontal top and bottom members 3 and

4 respectively may be connected to the studs to provide a frame work. The horizontal pieces 2 are embedded in a concrete wall 5, and it is to be observed that the concrete wall is of the thickness so that its opposed inner and outer faces terminate in spaced relation to the corresponding faces of the studs. Thus, when the inner and outer facing walls 6 and 7 are placed in position 60 against studding, dead air spaces 8 are provided between the partition wall and the facing walls. Such a wall, in my opinion, is not susceptible to the easy passage of cold or heat, is very rigid in construction, is 65 substantially sound proof, and is exceedingly durable. It is of course evident that the facing walls 6 and 7 may be of any construction. For instance, boarding may simply be nailed to the studding, after which 70 suitable surfacing material, such as brick, plaster or the like may be placed thereagainst.

It is thought that when the foregoing description is considered in connection with 75 the drawing, a clear comprehension of the invention will be had. For this reason, a more lengthy description is deemed unnecessary.

It is to be understood that while I have 80 confined the disclosure to a specific embodiment of the invention, minor changes coming within the field of invention claimed may be resorted to, if desired.

I claim:

A wall structure comprising a central partition wall composed of a wooden frame work including vertical studs arranged in staggered relation on opposite sides of horizontal connecting pieces, and a concrete wall 90 in which said frame work is embedded, the opposite sides of the concrete wall terminating in spaced relation from the outer surfaces of the vertical studs, and facing walls secured to said studding and spaced from 95 the concrete wall to provide dead air spaces between the facing walls of the concrete wall.

In testimony whereof I affix my signature.

PURVIS E. DEAN.
